Attorney.

UNITED STATES PATENT OFFICE

HORACE S. RHOADS, OF PHILADELPHIA, PENNSYLVANIA

SPRING FABRIC

Application filed November 8, 1927. Serial No. 231,800.

My invention is designed to provide an improved woven wire fabric of symmetrical and pleasing appearance adapted for use in the manufacture of bed springs, spring seats, 5 and the like. A leading object of my invention is to provide a fabric of wires so bent and interlaced as to prevent overlapping of the strands of laterally adjacent links and to maintain the strands of such links substantially parallel throughout the greater 10 part of their lengths; the distance between the strands of each link being decerased and rendered substantially uniform and the distance between the strands of adjacent links 15 being increased so as to improve both the appearance and the carrying capacity of the fabric.

In accordance with my invention, the fabric is formed by bending a strand of 20 wire of suitable weight and stiffness into a course or tier of links each comprising substantially parallel legs or shanks divergently crimped or offset at one end and connected by a cross-piece of greater length than the 25 distance between the bodies of the shanks. The links of each course are connected with one another at the ends opposite their cross members by loops having a diameter substantially equal to the offset resulting from 30 the crimping of the opposite ends of the adjacent link strands. The wire is bent so that the cross-pieces of the links and the loops are slightly above the general level of the fabric. The loops of one course of 35 links are laced or looped around the crimped ends of adjacent links of the succeeding course which are drawn together thereby adjacent to the cross-bars. The greater portion 40 of the lengths of the shanks are spaced in parallel relation.

The characteristic features and advantages of my improvements will more fully appear from the following description and the accompanying drawings in illustration of a preferred embodiment of my invention.

In the drawings, Fig. 1 is a top plan view of a bed spring made in accordance with my invention; Fig. 2 is an enlarged fragmentary 50 view of a portion of the fabric shown in Fig.

1; and Fig. 3 is a transverse sectional view on the line 3—3 of Fig. 2.

As illustrated in the drawings, my improved fabric is formed from a wire strand bent to form a row of links each comprising legs or shanks 1 and 2 having bent or crimped ends 1', 2' connected by the cross-piece 3. The leg 2 of one link is connected with the leg 1 of the next link by a loop 4 whose diameter is substantially equal to the space between the legs 2 and 1 of adjacent links when the crimped ends 2', 1' thereof are brought into juxtaposition. The loops 4 of one course of links closely embrace the crimped sections 2', 1' of the next course of links and draw 60 them closely together. The loops 4 and the crimped ends 2', 1' are bent upwardly, away from the general surface of the fabric, as illustrated in Fig. 3, so that the links of one course readily interlace with the links of the 65 succeeding course and the pressure of the loops 4 on the bent ends 1', 2' keeps such ends together but prevents their overlapping. The stiffness of the wire is so proportioned to the load to be carried by the fabric as to prevent the straightening of the crimped or bent ends 70 1', 2', which by their contact maintain the legs 1 and 2 in parallel relation substantially 75 throughout their lengths and a distance apart substantially equal to the diameter of the 80 loops 4.

As illustrated in Fig. 1, a fabric so formed may be advantageously utilized in the manufacture of a bed-spring having longitudinal frame members 5 and 6 connected by cross-pieces 7 and 8 provided with coiled springs 9 and 10 having hooks or loops thereon for the engagement of the links of my improved fabric. If desired, the lateral edges of the bed-spring may be reenforced by twisting a 85 supplementary wire 11 between the strands of the side meshes, and the end of the fabric terminating in free loops 4 may be reenforced by twisting a strand 12 therein.

By my improvements, the pulling and 90 pinching together of the strands of one course by the loops of the adjacent course is avoided and a symmetrical and rugged spring fabric is produced.

Having described my invention, I claim: 100

1. A spring fabric having courses of links with legs substantially parallel throughout the greater part of their lengths and ends offset divergently in each link and connected by cross members, the adjacent links being connected by loops, and the offset ends of adjacent links of one course being engaged by loops connecting adjacent links of another course.
10. 2. A spring fabric comprising courses of links having legs connected by loops, the opposite ends of the legs connected by a loop being bent toward one another a distance substantially equal to the diameter of said loops so as to maintain said legs substantially parallel when said bent portions engage one another.
20. 3. A spring fabric comprising courses of links having substantially parallel legs with divergently bent ends connected by cross members, the legs of adjacent links being connected by loops having a diameter substantially equal to the divergence of said bent ends, the loops of one course embracing the bent ends of the next course so as to maintain the legs substantially parallel throughout the greater portion of their lengths.
30. 4. A spring fabric comprising links having legs spaced by loops and each link having ends offset divergently, the loop connecting one pair of legs embracing the offset ends of another pair of legs so as to maintain the legs in substantially parallel relation.
35. 5. A wire fabric comprising a link having a pair of shanks, means for maintaining said shanks in parallel relation comprising curved loops located in one end of said link and ends offset divergently at the other end of said link.
40. 45. 6. In testimony whereof I have hereunto set my name this 29th day of October, 1927.
HORACE S. RHOADS.
